(57) **CLAIM**

The ornamental design for a liner engaging member for a trashcan, as shown and described.

DESCRIPTION

FIG. 1 is a front perspective view of a liner engaging member for a trashcan in accordance with the present invention;

FIG. 2 is a front elevational view thereof;

FIG. 3 is a side elevational view thereof, which is also representative of the opposite side view thereof;

FIG. 4 is a top plan view thereof; and,

FIG. 5 is a bottom plan view thereof.

That which is shown in the drawings comprises that which is claimed, namely, the design shown in the views of FIGS. 1–5. Any portion of the liner engaging member that is not shown in these drawings forms no part of the design for which patent protection is claimed herein. For purposes of understanding the context, use, and structure of the trashcan, reference is made to the above incorporated patent application disclosure.

The broken lines shown in the drawings form no part of the claimed design. The alternately dashed-dotted lines shown in the drawings are boundary lines, and form no part of the claimed design.
